UNITED STATES PATENT OFFICE.

DANIEL W. GORE, OF BUFFALO, NEW YORK.

TRAFFIC-SIGNAL.

1,354,249.

Specification of Letters Patent. Patented Sept. 28, 1920.

Application filed December 6, 1919. Serial No. 343,005.

To all whom it may concern:

Be it known that I, DANIEL W. GORE, a citizen of the United States, residing at Buffalo, in the county of Erie and State 5 of New York, have invented certain new and useful Improvements in Traffic-Signals, of which the following is a specification, reference being had to the accompanying drawings.

10 This invention relates to traffic signals and pertains more particularly to a device of this general character especially designed and adapted for use at street crossings, and it is an object of the invention to provide 15 a novel and improved device of this general character which may be readily and conveniently operated manually by the traffic officer.

It is also an object of the invention to provide 20 a novel and improved device of this general character including a semaphore or indicating device adapted to be moved or shifted into the requisite indicating positions, together with audible means operating 25 during the periods of movement of the semaphore or indicating member, so that the traffic officer is relieved of the necessity of blowing a whistle, as is now generally done.

The invention consists in the details of 30 construction and in the combination and arrangement of the several parts of my improved traffic signal whereby certain important advantages are attained and the device rendered simpler, less expensive and 35 otherwise more convenient and advantageous for use, as will be hereinafter more fully set forth.

The novel features of my invention will 40 hereinafter be definitely claimed.

45 In order that my invention may be the better understood, I will now proceed to describe the same with reference to the accompanying drawings, wherein:

Figure 1 is a view in perspective of a 45 signal constructed in accordance with an embodiment of my invention;

Fig. 2 is an enlarged horizontal sectional view taken through the casing and the part concomitant thereto;

50 Fig. 3 is a fragmentary view partly in elevation and partly in section, the line of section being substantially on the line 3—3 of Fig. 2;

Fig. 4 is a sectional view taken substantially on the line 4—4 of Fig. 3, and,

Fig. 5 is a fragmentary vertical sectional

view taken through the casing and the piston working therein.

As disclosed in the accompanying drawings, B denotes a base adapted to be rested 60 at a proper position at a street crossing or the like, and extending upwardly from the central portion of the base B is a standard S. The upper end of the standard S at the axial center thereof, is provided with an 65 elongated socket 1, in which is received the lower end portion of a vertically disposed standard or rod R. The standard or rod R is preferably circular in cross section with the socket 1 correspondingly formed, so 70 that the standard or rod R may be readily and conveniently rocked or rotated.

M denotes a semaphore or indicating member preferably comprising a rectangular frame affording the vertically disposed 75 side faces 2 upon which are suitably arranged the indications 3, such as "Go" and "Stop." The opposed indications 3 are similar, so that upon a quarter turn of the standard or rod R, as generally required at a 80 street crossing or intersection, the same indication or warning will be exposed to the traffic on the same street at opposite sides of the intersection.

The semaphore or member M, as herein 85 disclosed, has a frame centrally intersected by a cross member 4, provided midway its length with a sleeve or socket 5 to receive the upper end portion of the standard or rod R, and suitably locked thereto, so that 90 the semaphore or member M will rotate in unison with, and in the same general direction as the standard or rod R.

6 denotes an operating arm provided at one end with a sleeve or collar 6^a, through 95 which the standard or rod R extends, and said collar 6^a is suitably locked to the standard or rod R, and preferably through the instrumentality of the binding screws 7 threading said collar 6^a, and engaging the 100 standard or rod R. The outer extremity of the arm 6 is provided with a handle or hand grasp 8, preferably upwardly directed, whereby the requisite rocking or rotation of the standard or rod R may be conveniently 105 effected by the traffic officer.

C denotes a casing in top plan of the form of a sector of a circle, with the end walls 9 arranged substantially on an angle of 90°, and the inner vertical margins of said side 110 walls are connected by the elongated member 10. The member 10 extends below the

bottom wall 11 of the casing C, and said lower extended portion constitutes a split sleeve or barrel 12, having its edges defined by the outstanding flanges 14 with which 5 coat the binding members 15. The upper portion of the standard S extends within the split sleeve or barrel 12, and which sleeve or barrel is clamped to said standard S, whereby the casing C is supported in a 10 stationary position with respect to the device in its entirety.

The bottom wall 11 and the top wall 16 of the casing C at the apices thereof, are provided with the openings 17 through which 15 the standard or rod R is loosely directed. I also find it of advantage to interpose between the top wall 16 of the casing C and the collar 6^a, the spacing sleeve 18 surrounding the standard or rod R and riveted or 20 otherwise fixed to the top wall 16 of the casing C.

P denotes a piston arranged within the casing C and radiating from the portion of the standard or rod R within said casing. 25 The marginal portions of the piston contact with the bottom wall 11 and the top wall 16 of the casing C, and also with the outer or arcuate wall 19, so that when the standard or rod R is rocked, the air at the 30 side of the piston P, toward which said piston is moving, is placed under pressure to operate the whistle W or other pneumatic signal.

Each of the side walls 9 of the casing C is 35 provided with an opening 20, in which is suitably engaged an end portion of a whistle W or other pneumatic signal, so that the same will be caused to operate upon movement of the piston P in a direction thereto. Each of the side walls 9 is also provided with an induction port 21 with which 40 coacts a check valve 22, herein disclosed as of a flap type. When the piston P is moving in one direction air is drawn into the casing C at the side of the piston P, in which said piston is moving. The check 45 valve 22, at the side of the piston P in the direction of its travel, is maintained closed by the air compressed by the piston P in such movement.

As herein disclosed, the piston P comprises a metallic sheet of requisite dimensions folded centrally upon itself, to provide the overlying portions 24. The folded 55 portion of the sheet is cylindrical in form to provide a barrel 25 through which the standard or rod R extends, and said sheet, or more particularly the piston P, is clamped to the standard or rod R by the binding 60 members 26.

Interposed between the overlying portions 24 are the laminations 27 of suitable material, and the marginal portions of said laminations extend beyond the upper and lower 65 and the outer vertical margins of the pis-

ton P a distance sufficient for liberal contact with the bottom wall 11, the top wall 16 and the arcuate wall 19.

As is clearly illustrated in the accompanying drawings, the extended portions 17 of the laminations 27 are oppositely directed. The laminations 27 can be of any desired material, such as felt, sheet rubber, leather and the like. It is also to be noted that the side walls 9 are so constructed that 75 when the piston P is at the limit of its movement in either direction, no interference or obstruction is offered by the check valve 22 and the connected portions of the whistles W. 80

To further facilitate the desired movement of the piston P with the standard or rod R, the barrel 25 may be locked, as at 28, directly with the standard or rod R.

From the foregoing description it is 85 thought to be obvious that a traffic signal construction in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as 90 limiting myself to the precise arrangement and formation of the several parts herein shown in carrying out my invention in practice except as hereinafter claimed. 95

I claim:

1. A signal of the class described comprising a base, a standard rotatably supported thereby and provided with an indicating medium, a casing carried by the supporting member and provided with a check control induction opening, a pneumatic signal in communication with the casing, and a flat piston fixed to the standard and within the casing, said piston substantially radiating from the standard. 100

2. A signal of the class described comprising a base, a standard rotatably supported thereby and provided with an indicating medium, a casing carried by the supporting member, a pneumatic signal in communication with the casing, and a flat piston fixed to the standard and within the casing, said casing being also provided with a check control induction opening. 105

3. A signal of the class described comprising a standard supported for rocking movement, an indicating means coacting with the standard and provided with a check control induction opening, a casing supported independently of the standard, a 110 piston mounted within the casing and moving upon rotation of the standard, and a pneumatic signal in communication with the casing at opposite sides of the piston. 115

4. A signal of the class described com- 120

prising a standard supported for rocking movement, an indicating means coacting with the standard, a casing supported independently of the standard, a piston mounted 5 within the casing and moving upon rotation of the standard, and a pneumatic signal in communication with the casing at opposite sides of the piston, said casing at each side of the piston being provided with a

10 check control induction opening.

5. A signal of the class described comprising a standard for rocking movement, an indicating means coacting therewith, a casing supported independently of the 15 standard and through which the standard is directed, said casing being provided with a check control induction opening, a piston fixed to the standard and extending within the casing, and a pneumatic signal in 20 communication with the casing at each side of the piston.

6. A signal of the class described comprising a supporting standard, a second standard supported by the first standard for 25 rocking movement, an indicating means coacting with the second standard, a member

secured to the first standard, a casing secured to said member, said casing being provided with a check control induction opening said second standard being directed 30 through the casing, a piston fixed to the second standard and arranged within the casing, and a pneumatic signal in communication with the casing at opposite sides of the piston.

7. A signal of the class described comprising a supporting standard, a second standard supported by the first standard for rocking movement, an indicating means coacting with the second standard, an elongated member secured to the first standard, a casing secured to said member and provided with a check control induction opening, said second standard being directed 40 through the casing, a piston fixed to the 45 second standard and arranged within the casing, and a pneumatic signal in communication with the casing.

In testimony whereof I hereunto affix my signature.

DANIEL W. GORE.
